CUT-OUT DEVICE

Harry J. Lingal and Herbert J. Crabbs, Wilkinsburg, Pa., assignors to Westinghouse Electric & Manufacturing Company, East Pittsburgh, Pa., a corporation of Pennsylvania

Application September 23, 1936, Serial No. 102,084

14 Claims. (Cl. 200—121)

This invention relates to cut-out devices or circuit openers and particularly to that form of device in which a fusible wire is contained within a fibre tube.

5 It is an object of this invention to remove the fuse tube bodily from the contacts by which it is connected into the circuit when the fuse wire has melted.

10 It is a further object of this invention to initiate the movement of the fuse tube by devices controlled by the severing of the fuse wire.

15 It is a further object of this invention to mount the fuse tube in a box and to mount an indicator on the outside of the box, the position of the indicator being changed upon the separation of the fuse wire.

It is a further object of this invention to control the opening movement of the cover of the box by means of the fuse wire.

20 Other objects of the invention and details of the proposed structure will be apparent from the following description and the accompanying drawings, in which

Figure 1 is a longitudinal section of one form 25 of the device taken along the line I—I of Fig. 2.

Fig. 2 is a transverse sectional view taken on the line II—II of Fig. 1.

Fig. 3 is a transverse sectional view taken on the line III—III of Fig. 1.

30 Fig. 4 is a detail view showing a modification of the upper end of the cover and indicator.

Fig. 5 is a longitudinal sectional view of another form of the device taken on the line V—V of Fig. 6.

35 Fig. 6 is a sectional view taken on the line VI—VI of Fig. 5.

Fig. 7 is a sectional view taken on the line VII—VII of Fig. 5; and,

Fig. 8 is a perspective view of the lower mounting clasp shown in Fig. 5.

Referring to Fig. 1, the fuse is contained in a box 10 supported in any suitable manner, for example by means of a loop and pin extending through a hole 12. The box is of refractory or insulating material such as porcelain and has a cover 14 of molded insulating material secured thereon in any desirable manner, for example, by means of a pintle 15 through one end of the cover, preferably the lower end, and cooperating orifices in the sides of the box. Near the top of the cover it is provided with upstanding ears 17 which afford bearings for a pin 19 around which a spring 21 is coiled. One end of this spring bears against the outer surface of the main part 55 of the cover, as indicated at 23 and the other

end bears against a surface on the inner side of the indicator portion 25 of the cover, as illustrated at 27.

The indicator portion 25 of the cover is extended outwardly to form a projection 29 including a hole 31 into which a switch hook may be inserted for the manipulation of the device. The indicator has an arched portion shown at 33 which leaves a space between it and the cover 14.

In the interior of the box is the fuse tube 36 10 mounted on the cover 14 of the box. Any desirable way of mounting the fuse tube may be used, but I prefer an insert 38 molded in the material of the cover for holding the upper end of the fuse tube to the cover. The insert has threaded 15 holes into which screws 40 are inserted, under the heads of which a heart shaped cam plate 41 is secured. The lower end of the fuse tube is secured to the cover 14 by being inserted in a hole 28 in a projection 30 on the lower end of the 20 cover forming a part of the lower end wall of the box. The lower end of the plate 41 is arched as shown at 43 and bears against a bearing block or terminal 45 mounted near the upper end of the tube. 25

The heart shaped portion of the cam plate 41 is at right angles to the portion having the arched end 43. This portion contains a slot 47 which cooperates with the end knob 49 on the cap 48 of the fuse tube. It also contains two shallow 30 notches 50 one on each edge which engage with springs 52 mounted in the refractory box.

These springs are integral with each other being connected at the bottom or back of the box by a cross piece 54. The cross piece 54 is extended upward and bent to form a contact spring 55 which bears against the contact knob 49 on the fuse tube and is extended downward and secured by a rivet 57 to a second cross piece 59 which also extends upward to form a spring 60 40 which reinforces the spring 55 in the action against the knob 40. At the point where they are riveted together, the cross pieces 54 and 59 are widened into springs 61 which extend forwardly and occupy recesses 63 in the side walls 45 of the refractory box to retain the parts in the box. At the lowermost part of the cross pieces 54 and 59, they are secured to terminals 67 by which the power lines are connected to the device. Holes 69 are provided in the side walls of 50 the box for the introduction of such conductors.

Near the lower end of the tube a second block 71 is mounted on the tube 36. A lower terminal 68 is mounted in the housing by means of springs 72 which are similar in construction and mount-

ing to the springs 51. Mounted in contact with these springs 52 is a curved contact spring 53 which is riveted to the springs 52. An arm 75 extends from the block 71 on the fuse tube 36 toward the bottom or rear of the box. The arm 75 supports a pin 76 upon which is wound a spring 79. One end of this spring contacts with a rest 38 which extends rearwardly from the bottom of the block 71. The other end of the spring 79 contacts with an inwardly projecting rest 84 which is on one member of a U-shaped catch 85 pivoted on the pin 76. The cross piece 86 of the catch 85 is engaged by two hooks 89 which are mounted on the lower end of the indicator portion 25 of the cover.

The catch 85 projects through an opening 90 in the main part of door 14. Upon the end of the catch 85, that is, upon the central part of the cross piece 86 is mounted a terminal screw 92 which carries a nut 93 by which the end of the fusible wire 94 is secured in place, and electrically connected in the circuit due to the electrical contact between the ends of the catch 85 and the contact spring 53. The fuse wire 94 extends around the lower edge of the mouth of the tube 36 and into the tube and is integral with the fusible portion in the interior of the tube. The other end of the fuse wire is electrically connected to the terminal block 45 by the cap 48.

In the operation of this form of the device, when the wire 94 is fused, it releases the catch 85 and the catch moves upward under the influence of the spring 79 disengaging the hooks 89. This permits the indicator 25 on the cover 14 to move outwardly under the influence of the spring 21. In so moving, the hooks 89 draw the wire 94 away from where it is fused in the tube 36 thus lengthening and finally extinguishing the arc. The motion causes the cam surface 96 on the upper end of the indicator to come against the edge of the top of the box. This forces the upper end of the cover outwardly and pulls the plate 41 out of engagement, so that the springs 52 no longer engage the notches 50.

The whole cover is then free to move about the pivot 15 and carries the tube 36 with it, breaking contact between the contact springs 55 and 60 and the knob 41 and also between the contact spring 53 and the contact portion of arm 85. The motion of the cover and indicator together is through nearly 180° so that the tube is removed a considerable distance from the aforementioned contacts. If the material of the fuse tube affords a path over which the discharge 55 could leak, this is completely prevented by the long distance between these contacts and the terminals 41 and 92 on the fuse tube.

When the cover 14 is in open position the tube 36 on the inside of the cover is easily accessible and can be removed. To remove the tube 36 from the cover 14, the end of the tube having the plate 41 is first moved parallel to the cover 14, knob 49 passing out through the slot 47. When the plate 41 is free of the end of the tube 36, the tube can be drawn lengthwise out of the hole 28. A new tube with an unfused wire, or the old tube with a new fuse wire inserted through cap 48 can then be put in place. The lower end of the wire is fastened under the head 93 before the tube is replaced on the door. To replace the tube 36 on the door, the indicator portion 25 is moved into position against the main part 14 of the door and the end of the tube is moved longitudinally into opening 28 and the hooks 89 are engaged by catch 85 to hold the

indicator against its spring. The upper end of the tube is then moved laterally into engagement with slot 47.

If desired, the upwardly projecting cam portion 96 on the upper end of the indicator 25 may be omitted as shown in Fig. 4, and the indicator then will move outward when the wire 94 separates, but will not cause the plate 41 to be disengaged from the springs 52 so that the cover 14 will remain closed and the tube 36 will remain in place. When this modification of the device is used, the indicator 25 by its conspicuous position after the wire 94 has separated will call attention to the fact that the fuse has broken the circuit.

In the form of the device shown in Figs. 5 to 15 8, the parts having similar numbers to those already mentioned have the same functions and need not be described in particular. The fuse wire 94 in this form of the device is fastened at its lower end to screw 92 on the block 71, and 20 20 engages a hook 101 which holds the indicator 102 in the position illustrated in Fig. 5. Electrical contact with the lower block or terminal 71 is made by contact springs 103 which are supplemented by springs 104. These are secured by 25 rivets 57 in a way similar to the springs in Fig. 1, but the block 71 instead of having a rearwardly extending arm, as shown in Fig. 3, has its rear corners beveled as shown at 105 in Fig. 7, and similar corners 105 in the upper block 45 which 30 forms the other terminal contact with similar springs 103—104 there.

The indicator 102 is mounted on a pivot 106 in the cover. The indicator 102 has a tail extending above the shaft 106 and carrying a press bar 107. 35 Two springs 108 are mounted in recesses 109 in the cover and bear against the press bar 107. In addition to the tail in which the press bar 107 is mounted, the indicator 102 also contains a rearwardly extending hook 110 which engages a 40 latch spring 112, which is mounted as a part of a combination of springs similar to that shown in Fig. 8, near the top of the fuse tube 36. A cover 14 is pivoted at the bottom as shown at 15 as in Fig. 5, but the cover and not the indicator 45 contains the projection 29 with the hole 31 for the switch stick.

In the operation of this form of the device, when the wire 94 separates, it releases the hook 101 which permits the indicator 102 to move outward and releases the hook 110 from the latch spring 112.

The tube 36 is pressed outwardly by the springs 103 and 104 acting upon the beveled corners 105 of the lower block 71. This will press the tube 55 and the door outwardly enough to release the notches 50 in plate 41 from the springs 52 and the door is then free to rotate and can move about the pivot 15 its full 180° to a pendant position. The indicator 102 during its motion away from 60 the cover 14 drew the wire 94 out of the tube 36 breaking the arc if not already extinguished and leaving the tube free to be removed from the cover as in the other modification.

When it is ready to be returned, it can be closed 65 by a switch hook in the hole 31. The hook 110 will then engage the spring 112 and hold the cover in position. To insert a new fuse link 94, the tube 36 is removed from the door, the cap 48 is removed and a new fuse link 94 is threaded 70 through the tube, the upper end of the link is secured under cap 48, and the lower end is secured under nut 92. The tube 36 is then replaced on the door and the wire 94 is placed in retaining position under the hook 101.

If the springs 52 are formed to firmly engage the notches 50, the indicator 102 may move outwardly without the cover 14 departing from the illustrated position. The indicator 102 can then 5 serve to show the attendant that the fuse has blown without involving the fall of the cover 14 to the pendant position. If it is desired to avoid this result, the springs 52 may be slightly bent or removed so that no opposition to the outward 10 movement of the door is present when the spring 112 is once disengaged. The same result may be obtained by omitting the end of the plate 43 carrying the notches 50.

Many variations in the details of this device 15 will occur to those skilled in the art. The specific description and illustration of certain details is, therefore, not to be regarded as a limitation. The only intentional limitations are those set forth in the claims.

20 We claim as our invention:

1. In a circuit opener, a casing, a closure for the casing, a fuse tube within said casing secured to the closure, an indicator mounted to move separately from the closure and spring biased to a conspicuous position, the fuse tube including a fusible element having a part extending outside the tube, holding means biased to inoperative position and restrained by the outside portion of said element for normally holding the indicator 25 in inconspicuous position, said indicator being moved to conspicuous position upon release of said holding means by said fusible element, resilient means for starting the closure toward open position, and restraining means controlled by holding the indicator in said inconspicuous position, preventing said resilient means from affecting the door.

2. In a circuit opener, a casing, a closure for the casing, a fuse tube within said casing secured 40 to the closure, an indicator mounted to move separately from the closure and spring biased to conspicuous position, the fuse tube including a flexible, fusible element having a part extending outside the tube, holding means biased to inoperative position and restrained by the outside portion of said element for normally holding the indicator in inconspicuous position, said indicator being moved to conspicuous position upon release of said holding means by said fusible element, 45 resilient means for starting the closure toward open position, restraining means controlled by holding the indicator in said inconspicuous position preventing said resilient means from affecting the door, and means readily rendered ineffective which while effective permanently prevents said resilient means from acting on the door.

3. In a circuit opener, a casing, a closure therefor movable to open and closed positions, a fuse 50 tube having a fusible element therein carried by said closure, an indicator, means biasing said indicator from an inconspicuous position to a conspicuous position, said fusible element normally holding said indicator in inconspicuous position against the action of said biasing means, and means controlled by the position of said indicator for moving the closure to open position.

4. In a circuit interrupter, a housing, a door 55 for said housing movable to open and closed positions, a fuse tube mounted on the interior of said door and movable therewith, a fusible element within said fuse tube, a pair of spaced contacts within said housing adapted to be bridged by said fuse tube when said door is in the closed 70 position, at least one of said contacts normally

restraining said fuse tube and door against movement to the open position, an indicator movably supported on said door and biased to an indicating position, means restrained by said fusible element for holding said indicator in a normal 5 position, said indicator being operative upon release of said holding means by said fusible element to initially actuate said fuse tube out of engagement with the said one contact to enable said door to move to the open position. 10

5. In a circuit opener, a container, a closure therefor, an indicator on said closure, a fusible element, means on said indicator engaging said fusible element for holding said indicator in position against said closure, and means restrained 15 by said fusible element for moving said indicator into a position standing out from said closure upon fusion of said fusible element.

6. In a circuit opener, a container, a closure therefor movable to open and closed positions, 20 an indicator on said closure, a fusible element, latching means for holding said indicator in position against said closure, means biasing said latching means to the released position, said latching means being held in the latching position 25 against the action of said biasing means by said fusible element, means restrained by said latching means for moving said indicator into a position standing out from said closure, and means controlled by said indicator for holding said closure in closed position. 30

7. In a circuit opener, a container of refractory insulation and box-like form, a closure forming the cover of the box biased to open position, a fuse tube mounted on the interior of said closure, said fuse tube having a fusible element, a catch within said container, a latching member pivotally mounted on said closure adapted to engage said catch for holding said closure in closed position, said fusible element normally holding 40 said latching member in the latching position to secure said closure in closed position and release the same when said fusible element is fused, means near each end of the fuse tube for establishing connections thereto, said connections including the fusible element, whereby on fusing of said element, the closure will be released and the fuse tube removed from said connecting means. 45

8. In a circuit opener, a container of refractory insulation and box-like form, a closure forming 50 the cover of the box biased to open position, a fuse tube mounted on the interior of said closure, the mounting including a restraining device readily rendered inoperative, which when operative prevents movement of the closure to open position, said fuse tube having a fusible element, latch means biased to inoperative position and held by said fusible element in latching position to secure said closure in shut position and to release said closure when said fusible element is fused, said 60 latch means including an indicator biased to an indicating position, means near each end of the fuse tube for establishing connections thereto, said connections including the fusible element, whereby on fusing of said element the closure will 65 be released and the fuse tube removed from said connecting means.

9. In a circuit opener, a box-like container, a closure therefor pivoted thereto near one end, an indicator pivoted on said closure remote from 70 said end of the closure and biased to a position upstanding from said closure, a fuse tube within the container, a fusible element within said fuse tube, holding means carried by said indicator and engaged by said fusible element for keeping the 75

indicator close to the closure, said holding means being released upon fusion of said fusible element to permit movement of said indicator to said up-standing position, and means controlled by said indicator for initiating an opening movement of said closure.

10. In a circuit interrupter, a housing, a door for said housing movable to open and closed positions, a fuse tube mounted on the interior of said door and movable therewith, a fusible element within said fuse tube, a pair of spaced contacts within said housing adapted to be bridged by said fuse tube when said door is in the closed position, at least one of said contacts biasing said tube and door to the open position, an indicator pivotally mounted on said door having a latch member thereon, a catch supported within said housing adapted to be engaged by said latch member for holding said door in the closed position, said fusible element normally holding said indicator in the latched position and biasing means for moving said indicator to an indicating position upon fusion of said fusible element to thereby release said latch member from said catch and cause said one contact to initiate the opening movement of said door.

11. In a circuit interrupter, a housing, a door for said housing movable to open and closed positions, a fuse tube mounted on the interior of said door and movable therewith, a fusible element within said fuse tube, a pair of spaced contacts within said housing adapted to be bridged by said fuse tube when said door is in the closed position, an indicator pivotally mounted on said door, means biasing said indicator to an indicating position, a pivotally mounted latch member movable with said door and fuse tube operable when in the latching position for holding said indicator against movement by said biasing means, means including said fusible element for holding said latching member in the latching position, and biasing means for moving said latching member to the unlatched position upon fusion of said element for causing said indicator to be moved to the indicating position.

12. In a circuit interrupter, a housing, a door for said housing movable to open and closed positions, a fuse tube mounted on the interior of said door, a fusible element within said fuse tube, an indicator pivotally mounted on said door, means

biasing said indicator to an indicating position, a pivotally mounted latch member movable with said door and fuse tube operable when in the latching position for holding said indicator against movement by said biasing means, means including said fusible element for holding said latching member in the latching position, and biasing means for moving said latch member to the unlatched position upon fusion of said element for causing said indicator to be moved to the indicating position, said latch member withdrawing a portion of the fusible element from said fuse tube upon movement to the indicating position by said last named biasing means.

13. In a circuit interrupter, a housing, a door for said housing movable to open and closed positions, a fuse tube mounted on the interior of said door, a fusible element within said fuse tube, a pivotally mounted member carried by said fuse tube to which one end of said fuse element is secured, means biasing said member to place said fuse element under tension, an indicator pivotally mounted on said door and spring biased to an indicating position, and latching means including said pivotally mounted member for holding said indicator against movement toward its indicating position when said fusible element is normally under tension, said pivotally mounted member releasing said indicator upon fusion of said fusible element and causing a rapid separation of the fused ends of said fusible element.

14. In a circuit interrupter, a housing, a door for said housing movable to open and closed positions, a fuse tube mounted on the interior of said door, a fusible element within said fuse tube having a portion thereof extending exteriorly of said tube, an indicator pivotally mounted on said door, means biasing said indicator to an indicating position, and holding means carried by said indicator normally engaging said exterior portion of said fusible element for holding said indicator against movement by said biasing means, said biasing means moving said indicator to the indicating position upon fusion of said fusible element to cause said holding means to withdraw the lower portion of the fused fusible element from said tube.
